UNITED STATES PATENT OFFICE.

ELMER E. JENNE, OF ILION, NEW YORK.

MOISTENER FOR ENVELOPES AND THE LIKE.

Application filed May 22, 1922. Serial No. 562,733.

To all whom it may concern:

Be it known that I, ELMER E. JENNE, a citizen of the United States, residing at Ilion, in the county of Herkimer and State 5 of New York, have invented new and useful Improvements in Moisteners for Envelopes and the like, of which the following is a specification.

This invention relates to stationery devices 10 particularly to moisteners for stamps, envelopes and the like, and has for its object the provision of a novel device of this character embodying a water containing receptacle in which is partially submerged a 15 rotatable cylinder over which the gummed paper is drawn for effecting moistening thereof.

A very important object is the provision 20 of a device of this character in which the cylinder is carried by pivoted arms engaged by projections on a slidable cover, the arrangement being such that when the cover is in closed position the cylinder is swung down out of the way while when the cover 25 is in open position the cylinder will be swung up into its active or operative position.

An additional object is the provision of a 30 device of this character which will be simple and inexpensive in manufacture, highly efficient in use, durable in service and a general improvement in the art.

With the above and other objects and advantages in view the invention consists in 35 the details of construction to be hereinafter more fully described and claimed and illustrated in the accompanying drawings in which:

Figure 1 is a perspective view of the device 40 in operative position.

Figure 2 is a longitudinal section there- 45 through,

Figure 3 is a similar view with the cover in closed position and

Figure 4 is a cross section.

Referring more particularly to the drawings the numeral 10 designates a rectangular receptacle of any suitable size and material and having its top open and provided with 50 guides 11. At one end the upper edges of this receptacle are slightly cut away as shown at 12 and the upper edge of this end is formed with an inturned flange 13.

Pivoted at 14 against the inner face of 55 both sides of the receptacle are arms 15 which are formed with recesses 16 receiving

trunnions 17 on a rotary cylinder 18 which dips into the water within the receptacle. The other ends of these arms are inclined upwardly as shown and have inclined bearing 60 faces 19. Slidably mounted within the guides 11 is a cover 20 which is provided on its underside with a pair of cam like projections 21 engageable with the bearing faces 19 for swinging the arms 15 to elevate the 65 cylinder when the cover is slid to open position so that the cylinder will extend slightly above the cover at the cut away portion 12.

In the use of the device, assuming that the 70 cover is in open position and the cylinder elevated as above described, the envelope flaps, stamps or anything else to be moistened are drawn across the roller or cylinder whereupon the water adhering to the cylinder will effect the moistening. When the 75 use of the device is not desired the cover is slid into closed position whereupon the weight of the cylinder will cause it to swing down and be out of the way of the cover. When the device is thus closed it will be protected from dust and dirt so that it will 80 remain longer in a sanitary condition.

From the foregoing description and a 85 study of the drawings it will be apparent that I have thus provided a simply constructed and consequently inexpensive moistening device which will efficiently operate for the purpose specified and which owing to its peculiar construction and simplicity should have a long life.

While I have shown and described the 90 preferred embodiment of the invention it is of course to be understood that I reserve the right to make such changes in the form, construction and arrangement of parts as will 95 not depart from the spirit of the invention or the scope of the subjoined claims.

Having thus described my invention I claim:

1. A device of the character described 100 comprising an open topped receptacle, a pair of arms pivoted within the receptacle, a cylinder always partially submerged in water within the receptacle and covered when not in use and provided at its ends with trunnions detachably engaged upon said arms, 105 and a cover slidably upon the receptacle and formed with cam projections engaging said arms for effecting raising and lowering of the cylinder.

2. A device of the character described 110 comprising an open topped receptacle for

water, the upper edge of the opposite sides of the receptacle being partially cut away at one end, a pair of arms pivoted intermediate their ends upon the inner faces of opposite sides of the receptacle and having one end formed with recesses and their other ends formed with inclined bearing faces, a cylinder within the receptacle having trun-

nions receiving within said recess, a cover ¹⁰ slidable upon the receptacle and carrying cam projections engageable with said inclined bearing faces for varying the position of the arms and cylinder.

In testimony whereof I affix my signature.

ELMER E. JENNE.
